UNITED STATES PATENT OFFICE.

WILLIAM FROST, OF TALLULA, ILLINOIS, ASSIGNOR TO JOHN C. BOEKER, OF TALLULA, ILLINOIS.

COMBINED TAMPER AND CHARGER.

1,183,290.

Specification of Letters Patent.

Patented May 16, 1916.

Application filed March 1, 1915. Serial No. 11,389.

To all whom it may concern:

Be it known that I, WILLIAM FROST, a citizen of the United States, residing at Tallula, in the county of Menard and State of Illinois, have invented certain new and useful Improvements in Combined Tamperers and Chargers; and I do declare the following to be a full, clear, and exact description of the invention, such as will enable others skilled in the art to which it appertains to make and use the same.

My invention relates particularly to improvements in blasting devices, and specifically to a tool which may not only be used in applying the charge of blasting powder into a drill, but which may be employed for tamping or packing such powder after it is deposited in the drill.

The object of the invention is to provide a device of this character which will be simple and inexpensive, yet which will be very efficient in operation.

With this object in view, the invention resides in certain novel features of construction and combination hereinafter described and claimed and shown in the drawing wherein:

Figure 1 is a vertical section of the loaded charger showing the same in position to be forced into a drill made for its reception. Fig. 2 is a similar view with the tool inserted in the drill and the charge of the blasting powder discharged therefrom. Fig. 3 is a side elevation showing the positions of parts when the charger is being loaded with a charge of powder. Fig. 4 is a vertical transverse section as seen along the plane indicated by the line 4—4 of Fig. 1.

In this drawing, constituting a part of the application, numeral 1 designates a cylinder which is of the required proportions and which is preferably constructed of copper, brass or other material which will not cause sparks to be generated if forced against rocks or the like. The front end of the cylinder 1 is left entirely open, while the rear end thereof is closed by a centrally perforated end wall 2.

Mounted slidably within the cylinder 1, 50 is a conical tamper 3 whose apex is aligned with and disposed toward the perforation in the wall 2, while its base faces the open front end of said cylinder. In the present case, the tamper 3 is shown of approximately $\frac{2}{3}$ the length of the cylinder 1, which latter

is preferably about 18 inches in length. This allows 12 inches of blasting powder to be packed in said cylinder, when the tamper 3 is retracted therein as shown in Fig. 1, this amount of powder being sufficient for 60 what is commonly known as "one charge."

Secured in any appropriate manner to the rear end or apex of the tamper 3, is the front section 4 of an operating rod, said section being inserted through the perforation in the end wall 2 and having a forked hinge member 5 on its outer end, which member is so disposed as to limit the inward movement of the rod section 4, this preventing the tamper 3 from being forced forwardly 70 entirely out of the cylinder 1, this being expedient for reasons to become clear.

Pivottally connected at its front end to the hinge member 5, is the rear section 6 of the aforesaid operating rod, the rear end of 75 said section 6 being preferably equipped with a hand hold 7 to be grasped by the operator of the tool, thus facilitating the insertion of the latter into the drill or bore D which is formed in the bed B of rock or other 80 material to be blasted.

With the parts constructed as above described, the rear section 6 of the operating rod is folded toward the cylinder 1, as shown in Fig. 3, whereupon the open front 85 end of the latter is disposed upwardly. The tamper 3 is now retracted within the cylinder 1, and the latter filled with a charge of blasting powder in advance of said tamper. The fuse F, one of whose ends has previously been inserted in the charge of powder, 90 is extended into a notch 8 in the front end of the cylinder 1 and is then continued rearwardly in contact with, or in parallel relation with said cylinder, this fuse being of a 95 length equal to or greater than the length of the drill D.

With the charger loaded in the manner just described, the operator inserts the same into the drill D to approximately the position seen in Fig. 2. The operating rod is now rapidly reciprocated by the operator, thus causing the cylinder 1 to gradually work rearwardly upon the rod section 4, whereupon the powder is discharged into 105 the rear end of the drill. By proper manipulation of the tool, this powder may now be effectively packed or tamped, it being understood that the tamper 3 accomplishes this result. Needless to say, when the tool is 110

again removed from the drill, the fuse F is properly positioned for firing the charge. If more than one of such charges is necessary, it will be understood that the operation above described is repeated a proper number of times.

From the foregoing description, taken in connection with the accompanying drawing, it will be evident that although a very simple blasting device has been provided, the same will be very efficient in operation and will possess a number of advantageous features. It is essential that the cylinder 1, and probably the plunger 3 be constructed of material which will not cause the generation of sparks when forced into contact with rocks within the drill, since such sparks would undoubtedly explode the charge of powder prematurely, thereby causing serious results.

I claim:

A combined tamper and charger comprising a tube having one end closed, said end

being of substantially the same thickness as the tube, a plunger in said tube having a relatively short plunger rod secured to the plunger and extending through an aperture in said closed end, said plunger rod having a hinge member on its outer end disposed for contact with the outer side of said closed end to prevent projection of the plunger beyond the tube, and a relatively long handle rod disconnected with the tube and having at one end a hinge member connected to the hinge member of the aforesaid plunger rod, the other end of said handle rod being disposed at a point remote from the tube.

In testimony whereof I have hereunto set my hand in presence of two subscribing witnesses.

WILLIAM FROST.
